UNITED STATES PATENT OFFICE.

RAYMOND E. WHITE, OF NEWTON, MASSACHUSETTS, ASSIGNOR TO STEAM VEHICLE CORPORATION OF AMERICA, OF NEWTON, MASSACHUSETTS, A CORPORATION OF NEW YORK.

WATER-LEVEL INDICATOR.

Application filed June 3, 1925. Serial No. 34,597.

The invention in general relates to improved water level indicators. More specifically, my invention has reference to an improved water feed regulating system which 5 provides indicating mechanism, which may be placed at a point remote from the boiler itself, as, for example, on the dash of a steam vehicle, and the changes in level of the water within the boiler be accurately indicated by 10 the indicating mechanism. Although the present invention is particularly useful in connection with steam vehicles, it is, of course, to be understood that it may be used to equal advantage in any type of steam plant. 15 In practice, experiments and developments are being constantly made with a view of providing a more efficient control of the water level in a steam boiler. Those familiar with the present art know how important it is that 20 the water level in a boiler be under control at all times in order for the most efficient operation of the steam plant of which the boiler is a component. Then, too, it is well known that in order to preclude the possibility of 25 damage to the steam plant by the bursting of the boiler, it is absolutely necessary that accurate indicating means be provided for at all times in forming the attendant as to the level of the water within the boiler, so as to enable 30 the admission of water into the boiler to be controlled manually, should the automatic mechanism of the system fail to function properly.

The object of the present invention is to 35 provide an improved method of and apparatus for at all times indicating the level of the water within a boiler.

In the present invention the theory upon 40 which the whole control system operates, including the indicating mechanism, is that the rate of heat transmission from condensing steam or vapor in general to a conducting body is much greater than from liquid at the same temperature to the same conducting body. That is to say, the co-efficient of heat 45 transfer of condensing steam to a given body is greater than the co-efficient of heat transfer of water to the same body, even though the two are at the same temperature.

50 In accordance with the present invention I provide an external loop or connection between the steam space and the water space of

the boiler. The water in this loop assumes a level substantially the same as the main level in the boiler. The upper part of the loop 55 fills with steam.

This loop radiates heat from both the water filled and the steam filled portions. It loses heat far more rapidly from the steam filled portion because that portion will always be 60 maintained at substantially the temperature of the steam due to fresh steam flowing in to replace that which condenses. Hence the water at the water level in this external loop will always be at a temperature correspond- 65 ing to the temperature of the steam at a given pressure. The water from that point back to the water space of the boiler decreases in temperature due to radiation of heat as it moves back to the boiler.

I place at a suitable point in the water space of the loop a temperature sensitive element which may now be graduated in terms of water level, because the closer the water level in said loop is to the element, the hotter will 70 be the water as it arrives at said element. Since the rate of circulation of the water in said loop is a function of the rate at which heat is lost by radiation, atmospheric changes 75 in temperature for practical purposes are im- 80 material.

In the preferred form of my invention, I place the temperature responsive element of the water level indicator in the return circuit of the water level control automatics which 85 comprise a pair of water feed regulating units so positioned with respect to the boiler that for normal water level the lower unit is filled with water, and the upper unit is filled with steam. Both of these units control the ad- 90

mission of water into the boiler proper. Each of the units is equipped with a heat sensitive element which is adapted to expand when steam is applied thereto. In other words, the heat imparted into the element 95 by the steam is sufficient to cause it to expand. Since the upper unit is normally filled with steam, its heat sensitive element expands thereby connecting part of the water supply directly to the boiler. The lower unit normally contains only boiling water and hence its heat responsive element does not act to connect another part of the water supply 100 with the boiler, inasmuch as the heat imparted

thereto by the boiler water is not great enough to cause it to expand. That is to say, the part of the water supply associated with the lower unit is normally disconnected from the boiler and connected to a water reservoir.

When the water level in the boiler sinks to such a point that steam is permitted to enter the lower unit, the heat element of the said lower unit expands, to connect the other part 10 of the water supply with the boiler, so as to bring the level of the water within the boiler up to normal again, whereupon said supply is again disconnected therefrom.

In the present invention, the indicating 15 units are thermally controlled, i. e., temperature responsive devices and each includes a heat sensitive element which expands with variations of temperature imparted thereto. One of the indicating units is graduated in 20 terms of water level. The other unit which also responds to changes in the temperature of the water with which it is in contact, as will more fully appear as the description progresses, operates a visual signal i. e., a 25 lamp corresponding to low water level when the temperature exceeds a predetermined amount.

Other objects and advantages of the present invention will more fully appear from the 30 following detailed description taken in connection with the accompanying drawings, which illustrate one embodiment thereof, and in which:

Figure 1 is a diagrammatic view of a water 35 feed control system embodying the features of my invention;

Fig. 2 is an enlarged sectional view of one of the water regulating units;

Fig. 3 is an enlarged section taken on the 40 line 3—3 of Fig. 2;

Fig. 4 is an enlarged section taken on the line 4—4 of Fig. 2;

Fig. 5 is an enlarged section taken on the line 5—5 of Fig. 2;

Fig. 6 is an enlarged sectional view taken 45 on the line 6—6 of Fig. 1, illustrating in detail one of the indicating units;

Fig. 7 is a diagrammatic view illustrating the principle involved in the present invention; and

Fig. 8 is an enlarged view of the water level indicating gauge and its heat sensitive element.

Referring now to the drawings in detail, 55 in which like reference numerals designate similar parts throughout the several views, 10 denotes a water reservoir which may be of any suitable or usual construction. The reservoir 10 is connected by a pipe 11 to a condenser, not shown, which may be also of any suitable type. A pump 12 is connected by a suction line 13 with the reservoir 10. The pump is adapted to pump water through two water lines 14 and 15, which terminate 60 in check valves 16 and 17, respectively.

These valves, as shown, are preferably of the ball valve type and are adapted to prevent the steam from escaping from the boiler when the supply of water is disconnected therefrom. For safety sake it is always customary 70 to furnish each boiler with two water feeds in order to avoid accidents, should one of the feeds get out of order.

The check valves 16 and 17 are mounted in a pipe line 18 which is connected to a boiler 19. The end 20 of the pipe 18 preferably extends down into the boiler a considerable distance below the lowermost level to which the water may, at any one time, drop to. The boiler 19 is equipped with three gauge cocks 21, which may be used to ascertain the water level in the boiler in case of emergency, as is well known to those familiar with the present art.

The pipe line 14 is connected intermediate 85 its ends to a pipe line 22, connected to a water feed regulator, denoted generally by reference numeral 23, which will be more fully described hereinafter. The line 15 is connected intermediate its ends to an end of a pipe 24, which terminates at its other end in a water feed regulator 25, positioned above the regulator 23. Positioned in the pipe line 22 is a hand controlled valve 26 which may be of any usual type, and positioned in the line 24 is a 95 similar hand valve 27. These hand valves are adapted, in case of emergency, to be used to disconnect either of the lines 14 and 15 from the regulating units 23 and 25.

Referring now to Fig. 2, I have illustrated 100 on an enlarged scale and in section one of the water feed regulators. Inasmuch as the regulators 23 and 25 are identical in construction, a description of one will suffice for the other. The regulator includes a pair of distance rods 105 30 and 31, which are disposed in a parallel relationship. The rods are spaced a given distance apart and terminate at one end in a base member 32. One end of the rod 30 is mounted in a portion of the member 32 and 110 is held in place by a pair of lock nuts 34. Similarly, one end of the rod 31 is mounted in a portion of the member 32 and is held in place by lock bolts 35. The member 32 is equipped with a longitudinal aperture 36, 115 threaded at both ends. The member 32 in reality may be termed a coupling, if it is so desired.

The other ends of the rods 30 and 31 extend through apertures 40 and 41, respectively, of a movable coupling member 42. Threaded onto the rod 30 contiguous with the member 42 is a lock nut 42', and similarly threaded on the rod 31 is a lock nut 43. Threaded on the extreme end of the rod 30 125 is a nut 44 and threaded on the extreme end of the rod 31 is a nut 45. Encircling the threaded portion of the rod 30 intermediate the face of the nut 44 and the face of the member 42 is a spring 46, and likewise surround- 130

ing the threaded portion of the rod 31 intermediate the nut 45 and the member 42 is a spring 47. These springs at all times urge the member 42 towards the lock nuts 42' and 43, which afford stopping means therefore. Mounted on the rods 30 and 31 intermediate their ends is a cross head member 48 through which each of the rods pass. The cross head member 48 is adapted to be moved longitudinally on the rod, as will be more fully explained hereinafter.

The member 48 is equipped with a threaded longitudinal aperture 49 and a transverse aperture 50 (Fig. 4). The two apertures or bores 49 and 50 come together at the approximate center of the member 48.

Positioned in a longitudinal location intermediate the rods 30 and 31 is a tubular element 51 threaded at one end into the aperture 49 and at the other end into the aperture 36 in the member 32. The tube 51 is made of any suitable material adapted to expand at a predetermined temperature. The member 42 is equipped with a central longitudinal bore 52, into one end of which is threaded a plug seat 53, furnished with a countersunk bore 54. The seat plug 53 is provided with an annular shoulder 55 which abuts against the member 42 when the seat plug is threaded into the member. Projecting into the bore 52, is a valve stem 60 pinned at 61 to the member 48. Rigidly secured to the free end of the valve stem 60, inside of the bore 52, is a one-half diameter ball 62 which is adapted to be seated on portion 63 of the bore 54. The ball element 62 and the seat afforded by the plug seat member 53 constitute a valve, the purpose of which will be more fully explained hereinafter.

40 A bushing 65, a packing 66, a packing gland 67, and a packing nut 68 surround the valve stem 61. The bushing 65, packing 66, and gland 67 are located within the bore 52 of the member 42. These elements insure a tight 45 and proper fit for the valve stem and prevent any of the fluid medium from escaping from the valve around the wall of the stem. The packing nut 68 serves to maintain the gland in place about the valve stem.

50 As shown clearly in Figure 3, the bore 52 of the member 42 communicates with lateral aperture or bore 70 into which a pipe is threaded as will be more fully described as the description progresses.

55 Referring, now, back to Figure 1, it will be noted that bore 70 of regulator 25 is connected to one end of a pipe line 75 which discharges into the water reservoir 10. The aperture 70 of the regulator 23 is connected to one 60 end of a pipe line 76 which terminates or discharges into a condenser not shown. At this time, it should be noted that an end of the pipe line 24 communicates with the bore 54 of the plug seat 53 of the regulator 25 and the 65 pipe 22 communicates with the plug seat 53

of regulator 23. Suitable lock nuts 78 are provided for maintaining the ends of pipes 22 and 24 in their respective positions in the regulators 23 and 25. The bores 50 of both of the units or regulators 23 and 25 are connected to one end of a pipe line 80 which communicates at its other end with the boiler 19. The bores 36 of the members 32 are connected to a common pipe line 81 which communicates through an indicator, denoted generally 75 by reference numeral 82, with the lower part of the boiler 19.

The indicator 82 comprises a receptacle 83 having a drain cock 84 at its lower portion. Disposed within the receptacle 83 is a plug 80 84 filled with a sensitive fluid, such as nitrogen, and connected with a tube 85, which terminates in its upper end, is a measuring instrument 86. As shown in Figure 8, the instrument 86 is graduated to indicate the water 85 level within the boiler. That is to say, it points out whether the water level is high, normal, or low. The instrument, as shown, is of such a construction that it is adapted to be readily applied to the ordinary type of dash on steam vehicles. I have reference, more particularly, to steam automobiles, wherein it is desired to, at all times, have before you a picture of the position of the water 90 within the boiler.

Also connected in the pipe line 81, is an indicating element 90 connected at its upper end with an electrical circuit 91 which includes a battery 92 and a bulb or lamp 93. If the present invention should be applied to 100 an automobile, the battery of the automobile could be substituted for battery 92 and the lamp 93 would be mounted on the dash of the automobile. In Figure 6, I have shown in detail, the elements comprising the unit 90. 105 It consists substantially of a tube 100 mounted at one end in a plug 101 and at the other end in a socket-like member 102 provided with a centrally disposed opening 103. The plug 101 is provided with a bore 104 and is 110 threaded at 105 so as to enable it to be screwed into the pipe line 81 in any suitable manner. The plug 101 is also equipped with an annular shoulder 106 which is adapted to abut against the surface to which the heat element 115 90 is attached. Positioned within the tube 100 is a thermometer-like glass tube 107 in which a quantity of mercury is disposed. Any other heat responsive fluid could be used in place of mercury, without deviating 120 from the present invention.

The mercury thermometer 107 is equipped with a pair of fused platinum points 108 and 109 connected with leads 110 and 111 of circuit 92. It is apparent that when the mercury rises and stands sufficiently high enough to be in contact with both of the fuse points 108 and 109, circuit 92 will be closed and the light will be lit. Of course, as will be more fully explained hereinafter, the light only 130

becomes apparent when the water falls or sinks to a level beyond which it is considered unsafe for the water to drop.

The operation of the above described system is as follows:

Water is pumped from the reservoir 10 by the pump 12 through the pipe lines 14 and 15. The hand valves 26 and 27 are normally open, thereby permitting the water in the pipe lines to enter pipes 22 and 24 which discharge into the water regulators 23 and 25. It should be noted that the water regulators 23 and 25 are disposed in such a position as to have the extension of the normal water level line pass between them. This line is indicated by a dotted line in Figure 1. As a result, water from the boiler flows through pipe 81 into tube 51 of the lower regulator 23, but does not rise sufficiently high enough to enter the tube 51 of the regulator 25 when everything is normal. On the other hand, steam from the boiler 19 enters the pipe 80 which communicates with the apertures or bores 50 of the members 48 of each of the regulators. Inasmuch as tube 51 is already filled with boiling water, the steam only enters the tube 51 of the upper regulator 23. Each of the tubes 51 are adapted to expand at a predetermined temperature. In the present case, the boiling water hasn't enough heat or B. t. u. to cause the tube to expand to a very great extent, but the steam has a great enough amount of heat to cause either one or both of the tubes to expand. That is to say, upon the steam entering the tube 51, it tends to immediately condense. The heat of the condensation plus the heat of vaporization is sufficient to cause the tube to completely expand. The tube 51, in expanding, causes, through the valve stem 60, the valve of the regulator 25 to be closed. In other words, in moving the stem 60, the half-ball 62 is seated in its seat 63 in the plug 53.

By closing the valve of the upper regulator 25, the water in the pipe 24 cannot enter the pipe 75 which discharges into the reservoir 10. This results in the water in the pipe line 15 being pumped up through the check valve and pipe 18 into the top of the boiler 19. The check valve 17 is of any suitable construction and adapted to open upon water pressing against it on one side to permit the water to enter the boiler, but prevents any steam from escaping from the pipe line 18, through the pipe 15.

Thus, from the foregoing, it will be seen that normally when the water level is safe, water is being pumped into the boiler 19 by the pump 12 through one of the pipes 15. The water in pipe line 14, previously mentioned, passes through a hand valve 26 into the pipe line 22 which enters one end of the lower water regulator 23 through the plug seat 53 thereof. Since the tube 51 of this lower regulator 23 is normally in an unex-

panded position, the valve of this regulator is open, thereby permitting the water from the pipe line 22 to enter the bore 70 which is connected to pipe 76 discharging into the top of the condenser, not shown. That is to say, the water in the pipe line 14, when things are normal, does not get to the boiler at all, but through the medium of the lower regulator 23 is diverted into the condenser (not shown), where it may be utilized for cooling the condenser. The condenser discharges at its bottom into the pipe line 11 which communicates with the reservoir 10.

Should the water in the boiler drop to a level which is below the tube 51 of the lower regulator 23, naturally the water would not enter the tube 51, but would stand at the same level in the pipe 81, as the water is within the boiler. Steam, however, would then be permitted to enter both of the tubes 51 from the pipe 80. This would result in the lower tube 51 expanding in the same way as was described in the case of the first tube 51. The valve of the lower regulator would then be closed, thereby disconnecting the pipe line 22 from the pipe line 76 and resulting in the water in the pipe 14 passing through the check valve 16 into the pipe 18 and boiler 19. When the level of the water in the boiler was again at a sufficiently high level to fill the tube 51 of the lower regulator 23, its valve would open, thereby connecting the pipe 22 with the pipe 76 again, and cutting off the additional water supply from the boiler. Regulators 23 and 25 are thus enabled to, at all times, automatically control the level of the water within the boiler.

Referring now to Figure 2 again, it should be noted that the member 48 of each of the regulators is permitted to reciprocate on the rods 30 and 31 with the expansion and contraction of the tube 51. When the tube 51 contracts, the springs 46 and 47, naturally will expand. On the other hand, when the tube 51 expands, the springs 46 and 47, will be compressed. These springs aid in returning the tube 51 to its unexpanded or contracted position. The rods 30 and 31 are adjustable through the medium of lock nuts 34 and 35 and springs 46 and 47 may also be adjusted through the medium of nuts 44 and 45.

I shall now proceed to describe in detail the operation of indicating units 82 and 90. In order to make clear the operation of these units, I have illustrated diagrammatically, in Figure 7, the actual conditions involved. The regulators 23 and 25 afford considerable radiating surface for the fluid contained therein. When normal conditions exist, the water in the pipe 81 will extend clear up to the dotted extension line indicated in Figure 1. This line, as previously mentioned, is an extension of the normal water level line of the water within the boiler. It is well known

that when water changes into steam, it takes up an additional amount of heat known as heat of vaporization. Naturally when steam condenses, this additional amount of heat will be given off. This heat of vaporization may be very easily imparted into any adjacent body such as the tubes 51. As previously mentioned, the heat of vaporization is imparted to the tubes 51 to cause them to expand.

10 In order for the steam to condense, it is, of course, necessary that it have suitable radiating surface. In the present invention, the radiating surface is provided through the medium of the regulators 23 and 25. The 15 steam, upon entering the tube 51 of the upper regulator 25 in the pipe 81, readily condenses. Likewise, the boiler water in the regulators and pipe 81 is also cooled by the radiation of heat therefrom. Now, since the steam 20 and condensate above the water is, at all times, hotter than the water, heat will be imparted to the water. The amount of heat taken up by the water in this manner, of course, depends upon the amount of steam 25 condensing, or in other words, the greater the radiating surface afforded the steam, the greater will be the amount of steam condensed.

As the water line drops within the boiler, 30 so does the water in the regulator drop, permitting more steam to enter the regulators and the pipe 81, thereby bringing the steam temperature down closer to the point 82 resulting in a higher temperature at 82. 35 On the other hand, as the water rises, less steam is permitted to enter the regulators, resulting in less heat being imparted to the water or fluid matter in the pipe 81 and also affording a greater radiating 40 surface for the hot water. These variations in transmission of heat react upon the nitrogen or other fluid matter within the plug 84 and the tube 85 which, in turn, operates the dial of the gauge 86 in a well known manner.

45 From the foregoing, it will be evident that due to the radiating surface afforded the boiling water in the pipe 81 and water feed regulators, the temperature of this water will, under normal conditions, be considerably 50 lower than that of the steam condensate within the regulators. Therefore, the condensate upon coming into contact with the water imparts heat thereinto. The greater the amount of condensate, the greater will be the amount 55 of heat imparted to the water. Then, too, the condensate upon joining the adjacent water causes the water in the pipe 81 to move towards the boiler. That is to say, the condensing steam sets up a circulation in the 60 same manner as in the case of water glass gauges, as is well known to those familiar with the present art. By ascertaining the temperature of the water in the pipe 81, when the water level is normal, it is possible to 65 thereafter indicate the variations in water

level through the variations in heat since the water in the pipe 81 becomes hotter as the water level drops and cooler as the water level rises. I, in reality, employ the water in the pipe 81 as a conduction medium, the variations in heat of which control the indicating units 82 and 90. The hotter the water in pipe 81 becomes, the more the fluid in plug 84 and pipe 85 will expand, since the amount of expansion thereof is proportional to the 70 variations in temperature of the said heat sensitive fluid. Instead of employing a gauge graduated in terms of temperature, I employ one graduated in terms of water level. The terms I employ, as shown in Fig. 8, are 80 high, normal, and low, which denote corresponding conditions of the water in the boiler.

Should the steam, at any time, completely fill the tube 51 of the lower regulator 23, the heat imparted into the boiling water in the 85 pipe 81 will be great enough to cause the dial of the gauge 86 to swing over to indicate the low water level. That is to say, the dial of the gauge will point at the term "low" 90 thereon.

The variations in heat in the water in the pipe 81 react upon the mercury in the tube 107 (Figure 6) in much the same manner as they do upon the nitrogen plug 84. This tube 107 is so constructed that when steam completely enters the lower tube 51 of the regulator 23, the mercury within the tube will expand due to the increase in temperature of the water in pipe 81 to contact both of the points 108 and 109, thereby closing the circuit 100 92, and causing the light 93 to be lit. This forcibly attracts the attention of the attending operator, to warn him that the water in the boiler is at the lowest level it should be permitted to go. Obviously, by varying the 105 distance between the points 108 and 109, the level at which the lamp will light can be varied.

In case that either of the regulators 23 or 25 fail to function or become inoperative for 110 some reason or other, the hand valves 27 or 26 may be operated to connect or disconnect the pipe lines 14 and 15 with the boiler, as the case may be. These valves 26 and 27 are really for use in case of emergency. Moreover, if it were not for the light 93 and the gauge 86, the operator would have no way of telling when the water level within the boiler was below a safe amount, should the regulators prove ineffective, other than the cocks 115 21 on the face of the boiler. As previously mentioned, the use of cock gauges on a boiler involves considerable labor and also necessitates the constant use of them in order to be, at all times, aware of the conditions of the 120 water.

By merely referring to the gauge 86, one can ascertain, at any instance, the approximate water level of the water within the 130 boiler. Moreover, the attendant's attention

may be forcibly acquired by the lamp 93 when the level sinks below a point which is considered safe.

Although I have disclosed nitrogen as being the preferable medium in the case of the indicating unit 82 and mercury in the case of the indicating unit 90, I desire it understood that any other suitable heat sensitive fluid may be employed in place thereof.

10 Although I disclose the preferred embodiment of my control system, I desire it understood that my invention is not to be limited thereby, but only in so far as defined by the scope and spirit of the appended claims.

15 I claim:

1. In combination, a boiler having steam space and water space, a connection between the said spaces including a radiating surface for cooling the water and steam in the said connection, the steam in the said connection upon condensing being adapted to impart heat to the cooled water in the said connection, and means responsive to the heat of the water in the said connection for indicating 25 the approximate level of the water within the boiler.

2. In combination, a boiler having steam space and water space, a connection between the said spaces externally of the boiler including a radiating surface, the water within the connection being the same level as that of the water within the boiler, the water and steam in the said connection being cooled through the said radiating surface, and 30 means associated with the said connection responsive to the heat of the water within the said connection for indicating the approximate level of the water within the boiler.

3. In combination, a boiler having steam space and water space, a connection between the said spaces including a radiating surface for cooling the water and steam in the said connection, the steam in the said connection upon condensing being adapted to impart heat 40 to the water therein, the water in the connection being at the same level as the water in the boiler, and means including a thermal sensitive element responsive to the heat of the water in the said connection for indicating the level of the water in the boiler.

4. In combination, a boiler having steam space and water space, a connection between the said spaces externally of the boiler, a radiating surface in the said connection for cooling the water and steam in the said connection, the steam in the said connection upon condensing being adapted to impart heat to the cooled water, and means including an element containing a thermal sensitive fluid associated with the said connection below the normal level of the water in the boiler and responsive to the heat of the water therein for indicating the approximate level of the water within the boiler.

65 5. In combination, a boiler having a steam

space and a water space, a connection between the said spaces including a radiating surface for cooling the water and the steam in the said connection, the steam in the said connection upon condensing being adapted to impart heat to the cooled water, and means including a thermal sensitive element responsive to the heat of the water in the connection for indicating the level of the water in the boiler, said element being disposed in the lower part of the connection externally of the boiler and intermediate the water level of the boiler and the bottom of the boiler.

6. The method of measuring and indicating water level in a boiler which consists in connecting the water and steam spaces of the boiler, cooling the water and steam in the said connection causing the steam in the connection to condense, imparting heat from the condensed steam to the cooled water in the connection, and causing the heat imparted to the water in the connection by the steam to indicate the approximate level of the water in the boiler.

7. The method of measuring and indicating water level in a boiler which consists in connecting the water and steam spaces of the boiler, cooling the water and steam within the said connection, condensing the steam therein, causing the resultant condensate to impart heat to the cooled water, and causing the heat imparted to the water in the connection, to operate an indicator graduated in terms of the level of the water within the boiler.

8. The method of indicating water level in a boiler which consists in connecting the water and steam spaces of the water, cooling the water and steam in the said connection, causing the steam in the connection to condense, imparting heat from the condensed steam to the cooled water in the connection, causing the heat imparted to the water in the connection by the steam to indicate the approximate level of the water in the boiler, and operating a signal whenever the level of the water within the boiler drops below a predetermined amount.

9. The method of indicating water level in a boiler which consists in connecting the water spaces of the boiler, cooling the water and steam in the said connection, condensing the steam in the connection, causing the resultant condensate to impart heat to the cooled water in said connection, causing the heat imparted to the water in the connection to control the operation of an indicator graduated in terms of the level of the water within the boiler, and operating a signal by the heat of the water in the connection whenever the temperature thereof exceeds a predetermined amount to indicate that the water level in the boiler has dropped below a predetermined amount.

10. The method of indicating when the

water within the boiler has dropped below a safe level, which consists in connecting the water and steam spaces of the boiler, cooling the water and steam in the said connection, causing the steam in the said connection to be condensed, imparting heat from the condensed steam to the cooled water in the connection, and utilizing the heat imparted to the water by the condensed steam to operate a signal whenever the heat exceeds a predetermined amount to attract the attention of an operator.

11. In combination, a boiler having steam space and water space, a connection between the said spaces, signalling means, and heat sensitive means associated with the said connection below the water level in the boiler actuated by the heat conducted thereto from the said water and steam in the connection for operating the signalling means whenever the heat imparted to the water exceeds a predetermined amount.

12. The method of indicating water levels

in boilers consisting in, establishing communication between the steam and water spaces of the boiler, cooling the steam and causing it to impart its heat of vaporization to the water, and indicating variations in temperature in the water in terms of water level in the boiler.

13. The method of indicating water levels in boilers consisting in, subjecting a water column to the direct action of a superimposed steam column, varying the volume of steam in said steam column in accordance with variations in the water level in the boiler, cooling the steam of the steam column and causing it to impart its heat of vaporization to the water of said water column, and indicating variations in temperature in the water of the water column in terms of water level in the boiler.

In witness whereof, I hereunto subscribe my name this 27th day of May, 1925.

RAYMOND E. WHITE.
